UNITED STATES PATENT OFFICE.

FRANCESCO DURO, GIUSEPPE CRIVELLI, AND FRANCESCO PAMPUBO, OF MILAN, ITALY.

MACHINE FOR TRIMMING THE BRIMS OF HATS.

1,221,427.

Specification of Letters Patent.

Patented Apr. 3, 1917.

Application filed May 25, 1914. Serial No. 840,922.

To all whom it may concern:

Be it known that we, FRANCESCO DURO, GIUSEPPE CRIVELLI, and FRANCESCO PAMPUBO, subjects of the Kingdom of Italy, residing at Milan, Italy, have invented certain new and useful Improvements in Machines for Trimming the Brims of Hats, of which the following is a specification.

This invention relates to a machine for trimming the brims of stiff hats after they have been shaped, of the kind wherein the position of the cutter is automatically regulated by means of a cam or templet fixed to the hat holder, which latter is automatically stopped at given intervals. The machine chiefly comprises a lathe having a table which rotates in an elliptical path, a holder for the hats provided with a gage, an automatic clutch for stopping the holder after each revolution of the said holder, and an automatically adjustable cutter which trims the brims of the hats according to the gage.

In the accompanying drawings—

Figure 1 is an elevation of the machine showing all the essential parts but omitting some parts which are unimportant.

Fig. 2 is a plan of the hat holder.

Fig. 3 is an elevation of a speed reducer with double motion transmission.

Fig. 4 is a side elevation of the cutter.

Fig. 5 is a plan of the cutter.

Fig. 6 is a front elevation partly in section of the cutter.

Fig. 7 is a bottom plan view of the hat holder, and

Fig. 8 is a longitudinal section of said hat holder, taken on line 8—8, Fig. 2.

The cutter *f*. (Fig. 1), which has three crossed blades, is driven by means of a flexible shaft *X* from a main shaft *Z*, which latter is driven, in turn, from a motor or other suitable prime mover, (not shown). The shafts *X* and *Z* are connected by an intermediate shaft *Z'* having thereon a worm *W*, (Fig. 3), which meshes with and drives a worm wheel *Q*, the latter being connected by intermeshing bevel gears *Q'*, *Q*², with the vertical, uppermost or top section *X*² of a jointed shaft *X'*. This shaft *X'* consists, in the present instance, of three separate sections, whose confronting ends are connected by Cardan joints, the intermediate section *X*³ being disposed in an inclined position, while the lowermost or bottom section *X*⁴ is mounted horizontally. The last-mentioned section *X*⁴ is provided with a worm

T, (Fig. 1), which meshes with and drives a worm wheel *U*, keyed to a vertical shaft *A*, which is utilized to drive the lathe.

The worm wheel *U*, just referred to, is employed to automatically uncouple the hereinafter-described holder after each revolution of shaft *A*. For this purpose, said worm wheel has fixed to it a disk *o*, (Fig. 1), which is formed with a peripheral notch *p* and is designed for coöperation with a roller *r*, the latter being mounted on one end of a longitudinally-movable, horizontal rod *q*, carried in suitable bearings in the framework of the machine. Rod *q* is provided with a clutch-shifting fork *q'*, which is engaged with the movable member of a clutch *R*, that is mounted on the shaft section *X*⁴. The two members of this clutch tend normally to become disengaged, due to the expansive action of a spring, (not shown), which is interposed between said members and located interiorly of the same, said spring acting to press the roller *r* against disk *o*, so that when the said notch *p* in disk *o* comes opposite said roller, the latter will automatically enter thereinto, thus permitting the separation of the clutch members. The holder and its shaft *A* are again set in motion by hand, by means of the lever *y*, during the time necessary for roller *r* to leave notch *p*.

The hat to be trimmed is placed on the adjustable holder represented in Figs. 1 and 2, said holder being designed for rotation from or by the shaft *A* through the agency of suitable gearing connecting the upper end of said shaft with the base *P* of the holder and here shown as comprising a gear *B'* connected to the aforesaid shaft end and a gear *C'* driving the gear *B'* and located beneath and connected to said base *P*. The latter has mounted upon it a vertical pillar *O*, to whose upper end there is attached an elliptical cam or templet *F*, which is curved to conform precisely to the shape which the hat brim is to take, said cam serving to regulate the movements of the cutter in accordance with such shape, as hereinafter described. Upon this cam is mounted, in turn, the body of the holder, or holder proper, which preferably consists of four curved brass strips or sections *F'*, so shaped as to unite in forming an ellipse; each strip being provided with an inwardly-projecting rack member *F*². The four racks *F*² are disposed at 90° apart from one another, as

clearly shown in Fig. 2, and tangentially with relation to a central pinion F^3 , with which they all mesh, said pinion also meshing with a driving pinion F^4 . Both pinions F^3 and F^4 are connected in some suitable manner to cam F , and the second-named pinion is rotated by a crank F^5 , the arrangement being such, therefore, that rotation of pinion F^4 will be transmitted to pinion F^3 , and thence to the four racks F^2 , with the result that the latter are operated simultaneously and to equal extents, thereby effecting a corresponding adjustment of the holder sections F' . The sections F' are automatically returned to initial position by means of a pair of springs F^6 , (Fig. 2), which are connected to two of said sections located diametrically opposite each other, the retention of the sections in adjusted position being effected by means of a spring-controlled detent F^7 that is designed to engage a toothed segment or rack F^8 , (Fig. 7), rigidly connected to the driving gear F^4 . In the construction illustrated, the operating crank F^5 is directly secured to segment F^8 .

The lathe is equipped with a table, which, as previously stated, is designed to travel in an elliptical path, and carries the cutter f , the movements of the latter being controlled by the cam or templet F . To this end, the pedestal B^2 is provided at its top with a bed or base plate B formed with a pair of guides v , (Fig. 5), with which there is engaged a horizontal slide plate S , that is yieldingly forced upward, together with said bed plate, by a pair of vertical coil springs h , (Fig. 6), disposed in vertical sockets or recesses h^{12} in said pedestal, and, at the same time, yieldingly forced forward, or toward the hat holder, by a spring h' , (Fig. 4), the latter spring being interposed between a pair of depending arms C and D , the former of which is rigid with the bed plate B , and the latter with slide S . At its forward end, the slide S , which constitutes one member of the aforementioned table, is provided with a vertical spindle g , to which is pivotally connected the forward end of the upper table member L , the latter resting on slide S and, in turn, supporting the frame which directly carries the cutter. Upon the extreme forward end of said slide, is provided a roller z , mounted on a horizontal stud or pin and designed to ride along the under face of the cam F , against which it is held by the pressure of springs h ; while upon the forward end of the member or plate L there are arranged two rollers i and i' , mounted on vertical studs or pins at opposite sides of the spindle g , the last-mentioned rollers being yieldingly held against the peripheral edge of the cam by the pressure of spring h' .

In consequence of this arrangement, the said rollers i and i' are caused to ride along

the cam edge as the cam rotates, thus producing a reciprocatory movement of slide S and plate L , which constitute the lathe table, alternately toward and from the hat holder. At the same time, the bed plate, and with it the table L , S , alternately rises and falls, under the tension of the springs h , so that the resultant movement of the table, due to the combination of these two movements, being in an elliptical path. Furthermore, the action of the cam edge upon the aforesaid rollers i , i' , is such as to also produce a rocking or swinging movement of the plate L about the spindle g as a pivot; and as a result of such movement the cutter f , which is mounted horizontally in a suitable chuck m , has its axis maintained constantly in a direction normal to the curve of the cam, and, therefore, to the edge of the hat brim. The height of the aforesaid cutter above the table may be adjusted by means of a hand-wheel K , suitably connected with the body of the chuck; while the distance of the cutter from the hat holder may be similarly regulated by a hand-wheel K' . The upper portion of the frame or support, which carries the cutter and its adjusting appliances, is preferably made separate from the lower portion thereof, which is directly mounted upon the table, the two portions being connected by a hinge or pivot joint j , (Fig. 4), so that the former portion can be swung backwardly away from the hat holder when the cutter is not in use.

We claim as our invention:—

1. In a machine for trimming the brims of previously-shaped hats, the combination, with a hat holder having an elliptical gage whose size and shape correspond precisely to those which the trimmed brim is to take, and means for rotating said gage; of a cutter; driving means therefor; and a cutter-carrying table having means coöperative with said gage for causing said table to move in an elliptical path which coincides with the curve desired for said brim, during the rotation of said gage.

2. In a machine for trimming the brims of previously-shaped hats, the combination, with a hat holder having an elliptical gage whose size and shape correspond precisely to those which the trimmed brim is to take, and means for rotating said gage; of a cutter; driving means therefor; and a cutter-carrying table having separate means engaging the periphery and lower face of said gage, the combined engaging action of said means on said gage causing said table to travel in an elliptical path which coincides with the curve desired for said brim, during the rotation of said gage.

3. In a machine for trimming the brims of previously-shaped hats, the combination, with a hat holder having an elliptical gage whose size and shape correspond precisely to those which the trimmed brim is to take, and means for rotating said gage; of a cutter; driving means therefor; and a cutter-carrying table having means coöperative with said gage for causing said table to move in an elliptical path which coincides with the curve desired for said brim, during the rotation of said gage.

to those which the trimmed brim is to take, and means for rotating said gage; of a cutter; driving means therefor; and a cutter-carrying table having a roller engaging the 5 under face of the gage, and a pair of rollers engaging the periphery of said gage, the combined engaging action of said rollers on said gage causing said table to travel in an elliptical path which coincides with the 10 curve desired for said brim, during the rotation of said gage.

4. In a machine for trimming the brims of previously-shaped hats, the combination, with a hat holder having an elliptical gage 15 whose size and shape correspond precisely to those which the trimmed brim is to take, and means for rotating said gage; of a cutter; driving means therefor; and a cutter-carrying table having means coöperative 20 with said gage for causing said table to travel in an elliptical path which coincides with the curve desired for said brim, during the rotation of the gage, and for constantly maintaining the axis of the cutter 25 normal to the curve of said gage throughout such rotation.

5. In a machine for trimming the brims of previously-shaped hats, the combination, with a hat holder having an elliptical gage 30 whose size and shape correspond precisely to those which the trimmed brim is to take, and means for rotating said gage; of a cutter; driving means therefor; and a cutter-carrying table having means engaging the 35 under face of the gage, and separate means engaging the periphery of the gage, the combined action of the first- and second-named engaging means on said gage causing said table to travel in an elliptical path which 40 coincides with the curve desired for said brim, during the rotation of said gage, and the action of said second-named engaging means on said gage constantly maintaining the axis of the cutter normal to the curve of 45 said gage throughout such rotation.

6. In a machine for trimming the brims of previously-shaped hats, the combination, with a hat holder having an elliptical gage 50 whose size and shape correspond precisely to those which the trimmed brim is to take, and means for rotating said gage; of a cutter; driving means therefor; a cutter-carrying table having means coöperative with said gage for causing said table to travel in an 55 elliptical path which coincides with the curve desired for said brim, during the rotation of the gage; and means for automatically stopping the rotation of said gage after each revolution.

60 7. In a machine for trimming the brims of previously-shaped hats, the combination with a hat holder having an elliptical gage whose 65 size and shape correspond precisely to those which the trimmed brim is to take, and means for rotating said gage; of a cutter;

driving means therefor; and a cutter-carrying table pressed upwardly and forwardly toward said gage, said table having rollers simultaneously engaging the lower and peripheral faces of said gage, to control the 70 respective upward and forward movements of said table during the rotation of said gage, whereby said table is caused to travel in an elliptical path which coincides with the curve desired for said brim. 75

8. In a machine for trimming the brims of previously-shaped hats, the combination, with a hat holder having an elliptical gage whose size and shape correspond precisely to those which the trimmed brim is to take, and 80 means for rotating said gage; of a cutter; driving means therefor; a cutter-carrying table pressed upwardly and forwardly toward said gage, said table having rollers simultaneously engaging the lower and 85 peripheral faces of said gage, to control the respective upward and forward movements of said table during the rotation of said gage, whereby said table is caused to travel in an elliptical path which coincides with the curve 90 desired for said brim; and a clutch associated with said gage-rotating means and arranged to open automatically after each revolution of said gage, to terminate the 95 rotation of said gage.

9. In a machine for trimming the brims of previously shaped hats, the combination, with a hat holder having an elliptical gage whose size and shape correspond precisely to those which the trimmed brim is to take, 100 and means for rotating said gage; of a cutter; driving means therefor; and a cutter-carrying table comprising a member which is pressed simultaneously upwardly and forwardly toward said gage, and a member 105 pivotally mounted upon the first-named member to move therewith, said members having rollers engaging the lower and peripheral faces of said gage during the rotation of the latter, whereby said table is 110 caused to travel in an elliptical path which coincides with the curve desired for said brim, the rollers on the second-named member acting during such rotation to impart a swinging or rocking movement to that member, 115 to maintain the axis of said cutter constantly in a direction normal to the curve of said gage.

10. In a machine for trimming the brims of previously-shaped hats, the combination, 120 with a hat holder having an elliptical gage whose size and shape correspond precisely to those which the trimmed brim is to take, and means for rotating said gage; of a cutter; driving means therefor; and a cutter-carrying table comprising a member 125 slidably toward and from said gage and normally pressed both in an upward and in a forward direction, and a member superposed upon the first-named member and pivoted to the same 130

at its front end, said first-named member being provided at its front end with a roller engaging the under face of the gage, and said second-named member being provided at 5 its front end with a pair of rollers located at opposite sides of its pivot and engaging the peripheral face of said gage, said rollers acting to respectively control the upward and forward movements of said first-named member during the rotation of the gage, whereby said table is caused to travel in an 10 elliptical path which coincides with the curve desired for said brim, and the second-named

rollers acting to produce a rocking or swinging movement of the second-named member about said pivot, thereby to maintain the axis of said cutter constantly in a direction normal to the curve of said gage. 15

In witness whereof we have hereunto set our hands in the presence of two witnesses. 20
